UNITED STATES PATENT OFFICE

SEYMOUR TROY, OF BROOKLYN, NEW YORK

DESIGN FOR A SHOE SOLE FOR A WOMAN'S SHOE

Application filed September 19, 1930. Serial No. 37,019. Term of patent 14 years.

To all whom it may concern:

Be it known that I, SEYMOUR TROY, a citizen of the Republic of Poland, residing at Brooklyn, county of Kings, State of New York, have invented a new, original, and ornamental Design for a Shoe Sole for a Woman's Shoe, of which the following is a specification, reference being had to the accompanying drawing, forming a part thereof.

The figure is a bottom plan view of a shoe sole for a woman's shoe showing my new design.

I claim:

The ornamental design for a shoe sole for a woman's shoe substantially as shown.

SEYMOUR TROY.
